UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

COMMINUTING-MILL.

1,394,334.

Specification of Letters Patent. Patented Oct. 18, 1921.

Application filed August 23, 1917. Serial No. 188,258.

To all whom it may concern:

Be it known that I, RAY C. NEWHOUSE, a citizen of the United States, residing at Wauwatosa, in the county of Milwaukee and State of Wisconsin, have invented certain new and useful Improvements in Comminuting-Mills, of which the following is a specification:

This invention relates to improvements in the construction of mills for comminuting cement-making materials, coal, rock, ore and the like, and has particular relation to improvements in that type of comminuting mills known as combination mills.

An object of the invention is to provide a comminuting mill of the combination type, which is simple and compact in construction and efficient in operation. Another object of the invention is to improve the construction and operation of mills of the type disclosed in and the features of which are claimed broadly in application Serial No. 123,783, filed October 2, 1916.

One of the more specific objects of the invention is to provide a combination mill in which there is ample screening capacity between the successive comminuting chambers.

Another specific object is to provide a single means between two successive chambers of a combination mill, which will effectively serve both as a holdback for the grinding bodies and as a fine screening device for the discharge from the first chamber.

A further specific object is to provide means whereby the sizing screen and the division partition may be simultaneously adjusted longitudinally of the mill.

Still another specific object is to provide a durable, readily manufactured and readily renewable device for screening the material discharged from one of the grinding chambers and delivered into a subsequent grinding chamber.

Still another specific object is to provide means applicable especially to so-called wet grinding combination mills utilizing positive feeders, for preventing the feeding means between the successive chambers from pumping one of the chambers dry.

Some of the novel features disclosed but not specifically claimed herein form the subject of Patent No. 1,361,281, granted December 7, 1920.

A clear conception of several of the em-

bodiments of the invention may be had by referring to the drawing accompanying and forming a part of this specification in which like reference characters designate the same or similar parts in the various views.

Figure 1 is a central vertical section through a combination mill embodying a division partition which is adjustable along the length of the mill in order to vary the volumetric capacities of the several grinding chambers.

Fig. 2 is an enlarged fragmentary central vertical section through a combination mill of the dry type.

Fig. 3 is an enlarged fragmentary transverse vertical section through the mill, the section being taken along the line III—III of Fig. 2 looking in the direction of the arrows.

Fig. 4 is an enlarged fragmentary central vertical section through a combination mill of the wet type.

The combination mill illustrated in the drawing comprises a rotary shell 1 having feed and discharge end heads 2, 3 respectively, and provided with an adjustable partition dividing the shell into coarse and fine grinding chambers 5, 6 respectively. The mill is rotatably mounted in trunnion bearings 7, 8 and is adapted to be rotated by power applied to a driving gear 9, in the usual manner.

The coarse grinding chamber 5 is ordinarily filled substantially to the center line of the shell 1, with relatively large comminuting bodies or balls 10, while the fine grinding or finishing chamber 6 is likewise ordinarily half filled with relatively small comminuting bodies or balls 11. The balls 10, 11 are preferably formed of iron or other material having similar characteristics. The coarse grinding chamber 5 receives its supply of relatively coarse material through a feed trunnion 70 and delivers the material in partially reduced condition, through a combined holdback and sizing screen and past the division partition, to the finishing chamber 6 from which the finished product is delivered through a discharge screen 29 upon elevating vanes 12 which discharge the material from the mill through the discharge trunnion 80.

The combined holdback and screening device comprises a screen consisting of an annular series of spaced bars 14 extending

longitudinally of the shell 1 and detachably secured to a cast element 28 by means of an end retaining ring 17 and a front partition plate 18. The bars 14 are preferably fixedly spaced by means of distance pieces 30, 31 secured to the bar ends by welding or riveting. The shell 1 adjacent the screening device, is provided with an annular protecting lining or plate 27. The element 28 is provided with a series of conveying ribs 15 which are inclined relatively to the division partition, and which are located between the outer periphery of the screen and the inner periphery of the shell 1. The ribs 15 are connected by a ring 16 which also forms a continuous support for the mid portions of the screen bars 14. The screen bars 14 are so spaced by the pieces 30, 31, that any material passing therebetween is sufficiently fine to be further reduced by the relatively small grinding bodies in the finishing chamber 6. The bars 14 are preferably formed of wear-resisting material such as tool steel and may be formed by merely sawing or otherwise cutting bars of commercial tool steel into the proper lengths, and securing the distance pieces 30, 31 thereto.

The division partition comprises a pair of spaced annular plates 18, 20 between which are located a series of radial elevated vanes 4, the outer ends of which communicate with the spaces between the successive ribs 15 and the inner ends of which are directed toward a discharge cone or element 19. The plates 18, 20, the element 19, and the vanes 4 are firmly detachably united by means of clamping bolts 26.

In the form of division partition disclosed in Fig. 4, the plate 20 is provided with one or more annular series of perforations 21, and the plate 18 may be provided with similar perforations 25, the latter, however, being unnecessary. The perforations 21, 25 are preferably formed tapering away from the elevating vanes 4 in order to prevent clogging.

The coarse grinding chamber 5 is provided with relatively thick sectional liners 22, the liners directly adjacent the discharge screen being of less length than the others, as indicated in Fig. 1. The portion of the fine grinding chamber 6 directly adjacent the division partition is provided with relatively thick sectional liners 23 substantially like the short liners 22 of the chamber 5. The remaining portion of the chamber 6 is provided with relatively thin sectional liners 24, the junction of the liners 23, 24 being formed by liners of graded thickness. The liners 22, 23, 24, may be of equal thickness or they may be of different thicknesses as disclosed.

During the normal operation of the mill, rotary motion is imparted to the shell 1 and

the relatively coarse material is fed into the mill through the feed trunnion 70, being partially reduced in the coarse grinding chamber 5 by means of the balls 10. The partially reduced material passing the screen 70 bars 14 is delivered by the ribs 15 upon the outer ends of the revolving vanes 4, being elevated and delivered by these vanes 4 through the partition 20 into the fine grinding chamber 6. The material after being reduced to the proper fineness in the chamber 6 passes through the screen 29 upon the revolving vanes 12, which vanes elevate and deliver the final product from the mill through the trunnion 80.

If it is desired to vary the relative capacities of the chambers 5, 6, this may be done by adjusting the division partition longitudinally of the shell 1. Adjustment of the division partition may be effected by removing liners 22, 23 on one side of the partition or screen and after moving the partition and screen a sufficient distance to fill up the gap produced by the removal of these liners, the liners may be inserted in the mill on the opposite side of the adjusted elements. It will be noted that by forming the screen and the partition as disclosed, ample screening area is provided for the first chamber and the division partition may be adjusted without changing the relative locations of the screen and the partition. By forming the screen as an annular series of spaced bars 14, maximum screening capacity is obtained for minimum length of bars. 100 The bars 14 may be made of sufficient length to produce the required amount of screening capacity and may be readily formed from commercial stock. By utilizing the screen as a holdback as well as for screening purposes, the necessity of providing separate devices to perform these functions, is eliminated. The screening bars 14 may be readily removed and replaced when worn by merely removing the clamping bolts 26 and separating the coating elements.

It has been found in the operation of combination mills of the wet type wherein a positive feeding means was utilized between the successive chambers, that this feeding means would pump all of the liquid out of the coarse grinding chamber and would deliver it into the fine grinding chamber. In order to overcome this difficulty, the division partition may be provided with perforations 21, 25 as disclosed in Fig. 4, thereby permitting liquid to flow back from the fine grinding chamber 6 into the coarse grinding chamber 5. These perforations do not interfere with the normal feeding and permit 125 return to the first chamber of but a small proportion of the fine material by the liquid flowing therethrough.

It should be understood that it is not desired to be limited to the exact details of 130

construction herein shown and described, for obvious modifications within the scope of the appended claims may occur to a person skilled in the art.

5. It is claimed and desired to secure by Letters Patent:

1. In combination, a rotary shell, a partition dividing said shell into successive chambers having comminuting bodies therein, and means for positively feeding granular material past said partition in one direction, said partition being formed to permit free flow of fluid in either direction without permitting transmission of said comminuting bodies.
2. In combination, a shell rotatable about an axis, a wall having an opening adjacent to said axis, said wall dividing said shell into a plurality of chambers having comminuting bodies therein, and means for positively feeding granular material from one of said chambers into another through said opening, said wall being formed to permit free flow of fluid and comminuted material from either of said chambers into the other without permitting transgression of said comminuting bodies.
3. In combination, a rotary shell, a pair of transverse walls dividing said shell into successive chambers, said walls being spaced apart longitudinally of said shell to form an intermediate chamber which is free from

comminuting bodies and the other of said chambers adjoining said walls having a plurality of openings therethrough adjacent to 35 said shell, said openings being of a size adapted to prevent transgression of comminuting bodies to said intermediate chamber while permitting the passage of comminuted material through either of said walls, and 40 means within said intermediate chamber for elevating material delivered thereto through said openings.

4. In combination, a rotary shell, a pair of transverse walls spaced longitudinally of 45 said shell and dividing said shell into three successive chambers, the chamber between said walls being free from comminuting bodies and the remaining chambers having comminuting bodies therein, each of said 50 walls having a plurality of relatively small openings therethrough remote from the axis of said shell of a size adapted to prevent transgression of said comminuting bodies to said intermediate chamber but capable of 55 permitting free flow of comminuted material and fluid through said intermediate chamber, and means within said intermediate chamber for elevating granular material delivered thereto and for effecting 60 cascading of the elevated material.

In testimony whereof, the signature of the inventor is affixed hereto.

RAY C NEWHOUSE.
